UNITED STATES PATENT OFFICE.

CHARLES A. GONZENBACH, OF NEW YORK, N. Y.

NEEDLE-INSERTER FOR EMBROIDERING-MACHINES.

SPECIFICATION forming part of Letters Patent No. 764,119, dated July 5, 1904.

Application filed October 23, 1903. Serial No. 178,188. (No model.)

To all whom it may concern:

Be it known that I, CHARLES A. GONZENBACH, a citizen of the United States, residing in New York, borough of Kings, and State of New York, have invented certain new and useful Improvements in Needle-Inserters for Embroidering-Machines, of which the following is a specification.

This invention relates to an improved device for inserting simultaneously a gang of needles into a corresponding number of grippers of the well-known Swiss and other embroidery-machines.

In the accompanying drawings, Figure 1 is a perspective view of my improved needle-insertor for embroidery-machines. Fig. 2 is a perspective view of the guard-frame used in connection with the inserting device for separating the needle-threads after the needles are transferred to the grippers of the embroidery-machines. Fig. 3 is a vertical transverse section on line 3 3, Fig. 1, drawn on a larger scale. Fig. 4 is a vertical longitudinal section of a portion of the needle-inserting device on line 4 4, Fig. 3. Fig. 5 is a vertical transverse section on line 5 5, Fig. 6, through the needle-gripping mechanism of a Swiss embroidery-machine, showing my improved needle-insertor and guard-frame in position relatively to the grippers for transferring the threaded needles; and Fig. 6 is a plan view of Fig. 5.

Similar letters of reference indicate corresponding parts.

Referring to the drawings, A represents my improved device for inserting needles into the grippers of Swiss or other embroidery-machines, and B a guard-frame which is used in connection with the same. The needle-inserting device A is composed of two clamping-bars *a a'*, of sheet metal or other suitable material and preferably angular in cross-section, which are connected in such a manner that their horizontal portions are made to overlap each other, while their vertical portions are arranged parallel with each other, so as to form a hollow bar of U-shaped cross-section. The underlapping portion of the angular bar *a'* is provided with transverse grooves *a''*, which are of sufficient size for

holding the shanks of the needles used in embroidery-machines. The overlapping portion of the angular bar *a* is provided at its under side with a friction layer *a³* of elastic or flexible material, such as leather, felt, &c. 55 When the bars are clamped together, this friction layer of one bar overlies the grooves of the other and forms in connection with said grooves a series of sockets for the needles, one side of said sockets being composed of 60 rigid material, which accurately guides the needles, and the other side permitting the needles to be inserted freely in their sockets and exerting a frictional pressure thereon and preventing their slipping or dropping out of 65 the grooves. The overlapping portions of the angular bars *a a'* are provided with registering holes at points intermediately between the grooves *a''* for the needle-shanks, as shown in Figs. 1 and 6, and fastened together by 70 clamping-screws *d*.

The guard-frame B, that is used in connection with the needle-inserting device A, is made rectangular in shape, the horizontal rods *b* being connected by vertical partition-rods 75 *b'*, the distances of which from each other are equal to the distance between the needles of the embroidery-machine. The upper rod *b* of the guard-frame B is provided at its ends between the vertical rods *b'* with rubber sleeves 80 *e*, which rest with a certain degree of friction on the grippers when the guard-frame is placed in position over the same, as shown in Figs. 5 and 6. The guard-frame B is not connected with the inserting device, but is placed in 85 position over the needle-grippers in such a manner that the vertical partition-rods of the guard-frame are located midway between the grippers, as shown in Fig. 6.

Each needle-inserting device A is of sufficient length to permit the insertion of about twenty needles. Several needle-inserting devices are employed for each embroidery-machine, according to the number of needles in the same, and are filled with threaded needles 90 by inserting them into the grooves of the inserting device while the machine is running. The needles are first threaded by the girls and then placed into the inserting device A, so that the same is ready for use as soon as the 100

threads of the needles in the machine are gradually used up in the embroidering of the fabric. The embroidery-machine is stopped, the grippers are opened, the needles in the 5 same removed, and as many needles as are in one of the inserting devices transferred to the grippers. The grippers are then closed again by their operating mechanism. The needle-inserting device is then withdrawn from the 10 shanks of the needles that are firmly clamped by the grippers at their opposite ends, the clamping action of the grippers overcoming the frictional hold of the needles in the inserting device, so that a gang of needles and 15 their threads are thus transferred simultaneously to the grippers. The next set or gang of needles is then inserted into the adjacent set of grippers, and so on until all the grippers of the machine are provided with threaded needles.

The needle-inserting device is made of a convenient length, as many of them being used as required by the size of the embroidering-machine and the number of needles in the 25 same. After the threaded needles have been transferred to the grippers the guard-frame, which has been placed before the needles are transferred in inclined position over the grippers, as shown in Fig. 5, is then moved forward away from the grippers. The needle-threads, which during the inserting of the needles have been placed over the gripper-actuating eccentric, as shown in dotted lines in Fig. 5, are thereby pulled through the openings of the guard-frame and separated from 30 each other, one for each needle, and then dropped vertically below the needles, one thread being thereby separated from the other by the gradual motion of the needle-threads 35 through the open portions of the guard-frame and dropped into position, as shown in full lines in Fig. 5.

By my improved inserting device the grippers of embroidery-machines can be quickly 40 supplied with threaded needles at considerable saving of time and labor, the supply of threaded needles to the embroidery-machine being, furthermore, accomplished in a very convenient and satisfactory manner without

delay in the unraveling of the threads and replacing the individual needles in the machine. 50

Having thus described my invention, I claim as new and desire to secure by Letters Patent—

1. A needle-inserting device comprising two clamping-bars, one of said bars having transverse grooves on its inner face adapted to receive the needles, and the other bar having a friction layer on its inner face, serving to cover one side of said grooves and holding the needles therein by frictional contact therewith. 55

2. A needle-inserting device comprising two clamping-bars, one of said bars having transverse grooves on its inner face adapted to receive the needles, and the other bar having a friction layer on its inner face, serving to cover one side of said grooves and holding the needles therein by frictional contact therewith, and means for adjustably clamping said bars together. 60

3. The combination with a needle-inserting device provided with sockets for a gang of needles, of a guard-frame provided with partition-rods for separating the needle-threads after the needles are inserted into the grippers, substantially as set forth. 70

4. The combination, with a needle-inserting device provided with sockets for receiving a gang of needles, of a guard-frame composed of longitudinal rods and transverse partition-rods, and the upper longitudinal rods being provided with elastic sleeves, substantially as set forth. 75

5. In needle-inserting devices for embroidery-machines, a guard-frame for separating the needle-threads after the needles are inserted in the grippers, consisting of longitudinal rods and transverse partition-rods at a distance equal to the arranged distance between the needles and grippers of the embroidery-machines, substantially as set forth. 80

In testimony that I claim the foregoing as my invention I have signed my name in presence of two subscribing witnesses.

CHARLES A. GONZENBACH.

Witnesses:
